UNITED STATES PATENT OFFICE.

GUSTAVE M. GOLDSMITH AND CARL P. BARTELS, OF HAMILTON, OHIO, ASSIGNORS TO THE MOSLER SAFE COMPANY, OF HAMILTON, OHIO, A CORPORATION OF NEW YORK.

PRESSURE SYSTEM FOR SAFE OR VAULT DOORS AND THE LIKE.

Application filed September 23, 1921, Serial No. 502,723. Renewed August 18, 1923.

To all whom it may concern:

Be it known that we, GUSTAVE M. GOLDSMITH and CARL P. BARTELS, citizens of the United States, residing at Hamilton, Butler County, Ohio, have invented certain new and useful Improvements in Pressure Systems for Safe or Vault Doors and the like, of which the following is a specification.

This invention relates to pressure systems for safe or vault doors, and the like, and, in particular, relates to a pressure system adapted to be internally adjusted into operable or into inoperative condition for closing or for preventing the closing of the safe or vault door on which the system is mounted. Our invention further relates to a power transmission device adapted to be associated with a pressure system so as to be operable to establish or to disable a driving connection between a driving element, such as the pilot wheel and a driven element, such as the worm shaft, of the pressure mechanism.

This invention is broadly similar to the invention covered in our application filed on September 23, 1921, Serial No. 502,623 relating to improvements in pressure systems for safe or vault doors and the like.

The pressure system of a vault or safe is a mechanism carried on the outside of the vault or safe door whereby the vault door may be forced into absolutely closed position and thus enable the locking bolts to be operated to lock the vault. The mechanism is adapted to be driven by rotating a hand wheel, commonly called the pilot wheel, this wheel being customarily in permanent, driving engagement with a worm shaft which connects through a series of gearing with a plurality of rotatable pressure bars carrying cams adapted to engage with bars or blocks mounted on the door frame. The construction is such that when the pilot wheel is rotated the pressure bars revolve and the motion of the cams against the bars or blocks produces great pressure and forces the door into absolutely closed position in the door frame or jamb. Any one may operate such a pressure system by merely turning the pilot wheel. Thus no protection is given to a person within the open vault from being locked inside by an unauthorized person

such as a daylight bank robber. One of the objects of our invention is to provide a pressure system incorporating means, preferably concealed and operable in a secret manner whereby the system may be readily and easily adjusted into operative or into inoperative condition, thereby enabling an authorized person before entering the vault to adjust the system into inoperative condition, and enabling such person to restore the system into operative condition when he desires to do so. A further object of our invention is to provide a device of the character described wherein the adjusting means are so mounted that they are not readily apparent to a casual observer and are controlled by the operation in a special manner of one of the usual elements of the system, such as one of the handles of the pilot wheel. More specifically our objects include the provision of a power transmission mechanism whereby a driving connection may be readily and easily established or be disabled between a driving element, such as the pilot wheel of a pressure system, and a driven element, such as a worm shaft of such system, the presence of the transmission device being concealed.

One of the advantages obtained by providing a pressure system which may be secretly adjusted into operative or into inoperative condition, is that when the system is adjusted into inoperative condition unauthorized persons, such as bank robbers, not familiar with the anti-locking device, are preventing from working the system to close the vault door and are prevented from locking employees of the bank in the vault after attempting burglary.

Other advantages and objects will be in part obvious and in part pointed out herein-after.

In accordance with our invention instead of mounting the pilot wheel of the pressure system in permanent engagement with the worm shaft thereof, as has heretofore been customary, we mount the pilot wheel for free rotation on the worm shaft and provide a power transmission device operable to establish or to disable a driving engagement between the pilot wheel and the worm shaft of the system. For operating the device I

provide a member which is preferably disguised or concealed, and such member may advantageously comprise one of the handles of the pilot wheel. The power transmission device may comprise a dog or key mounted on the pilot wheel for movement into or out of any one of a number of suitable recesses provided in the periphery of a circular plate which is fixedly mounted on the 10 worm shaft, with the result that when the dog is in a recess the pilot wheel is locked to the worm shaft and when the dog is out of the recess the pilot wheel is unlocked from the worm shaft and an operative connection between the wheel and shaft is correspondingly made or broken. Preferably the locking dog is carried on the inner end of a plunger slidably mounted on the pilot wheel and having a flange at its upper 20 end adapted to be engaged by a helical thread or cam member carried on a pin which comprises an extension of one of the handles of the pilot wheel. The construction is such that when the handle is rotated 25 to a certain extent about its axis the helical thread engages the flange on the plunger and effects the movement of the dog out of locking engagement in a recess of the plate attached to the worm shaft, while by 30 continuing or reversing the rotation of the handle the flange on the plunger will ride off of the helical thread on the pin and allow the locking dog to move into locking engagement in a recess of the plate. Preferably, a coil spring is arranged about the 35 plunger and is compressed between the dog and a shoulder carried on the pilot wheel. The spring continually urges the dog to move toward a recess, so that when there is no recess in alignment with the dog, the handle may nevertheless be operated to release the plunger and allow the spring to move the dog into a recess as soon as a recess is brought into alignment therewith. 40 By locking the dog carried on the pilot wheel into a recess of the plate attached to the worm shaft the pressure system is adjusted into operative condition and the system may be operated to close the vault door. 45 Likewise by removing the dog from a recess of the plate the pressure system is adjusted into inoperative position and it may not then be operated to close the vault door. The entire device may be concealed and held 50 in position by a substantial cover plate on the back of the pilot wheel and since the handle of the pilot wheel which operates the power transmission device appears to be exactly similar to the other handles of the wheel, the presence of the anti-locking device may be hidden from an unauthorized person.

In order that a clearer understanding of our invention may be had attention is hereby directed to the accompanying drawings

forming a part of this application and illustrating one possible embodiment of our invention.

Referring to the drawings, Fig. 1 is a front elevation, somewhat diagrammatical, 70 of a pressure system embodying our invention, mounted on a door of a vault; Fig. 2 is a plan view of a portion of the pressure system with certain parts broken away for clearness; Fig. 3 is a sectional view of a 75 portion of the pressure system including the power transmission device; Fig. 4 is a section taken on the line 4-4 of Fig. 3; Fig. 5 is a section taken on the line 5-5 of Fig. 3. Similar reference characters designate 80 similar parts throughout the several views of the drawings.

Referring to the drawings, 1 indicates the front wall or door frame of a vault or safe, with a vault door 2 hinged thereto by means of suitable hinge mechanism 3. On the outside of the door 2 is mounted a pressure system comprising steel pressure bars 4 mounted for rotation in bearings 5 on the outside of door 2, and having at their outer ends cams 6 adapted to engage with bars or blocks 7 attached to the door frame 1. A series of gearing 8 permanently connects pressure bars 4 to a worm shaft 9, which is mounted for rotation on door 2. Power is transmitted to the mechanism by means of a hand wheel 10 which is fitted with a plurality of handles 11. Wheel 10 is mounted for free rotation on shaft 9, operable means being supplied whereby the wheel 10 may be locked to or be unlocked from the shaft 9 to establish or to disable a driving connection therebetween. As illustrated in the drawings, this power transmission device comprises a ratchet wheel 12 fixedly attached to worm shaft 9 as by means of a pin 22 penetrating a perforation in a hub 23 formed on the wheel 10 and a perforation in shaft 9. The periphery of wheel 12 is provided with a plurality of recesses 13 adapted to receive a dog or key 14 carried on the end of a plunger 15 which is slidably mounted on the pilot wheel 10 and in permanent engagement therewith. The upper end of plunger 15 is provided with a radially extending flange 16 which is adapted to be engaged by a helical cam or square thread 17 provided on a pin 18 carried on and extending axially from the inner end of one of the handles 11' of the pilot wheel, so that by rotating the handle 11' the thread 17 moves to raise or to lower the plunger 15 and to correspondingly cause dog 14 to move out of or into a recess 13 of wheel 12.

The operating handle 11' and the pin 18 are axially rotatable on wheel 10 and are preferably held in position thereon by a removable section 24 on the rim of the pilot wheel, this section being preferably accu- 125

rately machined to serve as a bearing and guide for the pin 18 and plunger 15.

Handle 11' may be integral with or may be securely attached to the top of pin 18 by any suitable means, pin 18 being provided with an annular shoulder portion 19 adapted to seat within a suitable groove or recess 19' in the pilot wheel to prevent the pin and handle from being withdrawn therefrom. The dog 14 may be guided in a groove 27 which is milled in a lug 28 on the back of wheel 10. About the plunger 15, and compressed between the dog 14 and a shoulder 21 provided on the pilot wheel is a coil spring 20 adapted to continually urge the dog 14 to move toward ratchet wheel 12 and into one of the recesses 13, and to accomplish such movement whenever the thread 17 releases the plunger 15 to the action of this spring.

Preferably the entire device is concealed and held in position by means of a substantial cover plate 26 secured to the back or under side of the pilot wheel 10. If desired, an ornamental nut 25 may be supplied to cap the outer end of the worm shaft 9.

The operation of the device is as follows: When the device is in the position illustrated in Fig. 4, wherein the dog 14 is seated within a recess 13, the pilot wheel 10 is locked to the worm shaft 9 so that by rotating the pilot wheel the pressure system may be operated and the vault door closed. To disable the mechanism, the handle 11' is turned on its axis. This operation will turn pin 18 and drive the lower end of the helical cam 17 into engagement with the flange 16 of the plunger 15. By continuing to turn handle 11' the flange 16 will ride upward on the cam 17 and the dog 14 will be withdrawn from locking engagement in the recess 13. Now the pressure system is disabled, and the pilot wheel 10 may be rotated freely about the worm shaft 9 but cannot operate the pressure system, thus preventing the vault door from being closed. To again restore the device into operative condition, it is only necessary to continue the turning of handle 11' until flange 16 slips off the upper end of the helical thread 17, thereby releasing the plunger 15 to the action of spring 20 and in consequence plunger 15 will move toward shaft 9 and the dog 14 into a recess 13, just as soon as a recess is in alignment with the dog. A slight rotation of the pilot wheel will soon bring a recess 13 under the dog 14 if such recess is not so positioned when the handle 11' is operated to free flange 16 from thread 17. As soon as dog 14 enters recess 13 the pressure system is again in operative condition and the vault door may be closed by rotating the hand wheel 10.

Preferably the device is so arranged that by twisting the handle 11' through ninety

degrees the thread 17 on the collar pin 18 will travel sufficiently under the flange 16 of the plunger 15 to lift the dog 14 out of a recess 13. Upon twisting handle 11' more than the ninety degrees the flange 16 will ride off the top of the cam thread 17 and by reason of the action of spring 20 the dog 14 will be again brought into mesh with the ratchet wheel 12.

As many changes may be made in the above construction and many apparently widely different embodiments of this invention can be made without departing from the scope thereof, it is intended that all matter contained in the above description or shown in the accompanying drawings shall be interpreted as illustrative and not in a limiting sense.

What we claim is:

1. In a pressure system for safe or vault doors or the like, the combination with a worm shaft, a pilot wheel rotatably mounted on said shaft and a handle rotatably mounted in said wheel, of means whereby a driving connection may be established or may be disabled between said pilot wheel and said worm shaft in response to predetermined rotation of said handle on said wheel.

2. In a pressure system for safe or vault doors or the like, the combination with a worm shaft and a pilot wheel for driving said shaft, of a ratchet wheel fixed to said shaft and having a recess, and means including a dog mounted on said pilot wheel for movement into or out of said recess to establish or to disable a driving connection between said pilot wheel and said worm shaft.

3. In a pressure system for safe or vault doors or the like, the combination with a worm shaft and a pilot wheel for driving said shaft, of a handle rotatably mounted on said wheel, a ratchet wheel fixed to said shaft and having a peripheral recess, means including a dog mounted on said wheel for movement into or out of said recess to establish or to disable a driving connection between said pilot wheel and said worm shaft and means for moving said dog into or out of said recess in response to predetermined rotation of said handle.

4. In a pressure system for safe or vault doors or the like, the combination with a worm shaft and a pilot wheel for driving said shaft, of a handle rotatably mounted on said wheel, a ratchet wheel fixed to said shaft and having a peripheral recess, means including a dog mounted on said wheel for movement into or out of said recess to establish or disable a driving connection between said pilot wheel and said worm shaft and means for moving said dog into or out of said recess in response to predetermined rotation of said handle, said last mentioned

means including a plunger attached to said dog and having a flange, a pin rotatable with said handle and having a helical thread adapted to engage said flange and 5 adapted when rotated to raise and lower said plunger and dog, and a spring urging said dog to move into said recess.

This specification signed and witnessed this 20th day of September, 1921.
